UNITED STATES PATENT OFFICE.

JOHN WEST, OF BROOKLYN, NEW YORK.

DESIGN FOR A FONT OF TYPE.

SPECIFICATION forming part of Design No. 15,610, dated December 9, 1884.

Application filed July 17, 1884. Term of patent 14 years.

To all whom it may concern:

Be it known that I, JOHN WEST, of Brooklyn, in the county of Kings and State of New York, have invented and produced a new and original Design for a Font of Type, of which the following is a full, clear, and exact description.

Reference is to be had to the accompanying impression, forming a part of this specification, which shows my newly-designed font of type.

In my newly-designed font of type the bases of nearly all of the lower-case are straight and shaded, while the parts above the base are light lines and form an angular junction with the base-lines. The characteristic of the straight shaded base is preserved in the capi-

20 tals B C D E K L M N R U X. The vertical strokes of the majority of the letters composing the upper-case begin with a hair-line and terminate in a shaded portion that forms an angle with the straight shaded base. A shaded flourish on the top part of a major portion of the upper-case also forms a distinguishing feature of my design.

25 What I claim as new, and desire to secure by Letters Patent, is—

The design for a font of printing-type, as shown and described.

JOHN WEST.
